SIGNAL LANTERN OR SIMILAR ARTICLE

John O. Lockwood, Grand Rapids, Mich., assignor, by mesne assignments, to Bly Corning, Flint, Mich.

Filed Nov. 12, 1959, Ser. No. 58,311

Term of patent 14 years

(Cl. D48—24)

The sides of the signal lantern not shown are substantially the same in appearance as the sides shown.

I claim:

The ornamental design for a signal lantern or similar article, as shown and described.
